Claims priority, application France Apr. 29, 1957

7 Claims. (Cl. 313—131)

The present invention relates in general to spark plugs of internal combustion engines and has specific reference to an improved low-tension spark plug.

It is already known to constitute the sparking element of spark plugs utilized for igniting the fuel mixture in internal combustion engines by the discharge of a condenser in the form of a pair of electrodes spaced .004" to 0.012" apart, this gap being occupied by an insulating member on which the ignition spark is caused to slip.

The assembly comprising the electrodes and insulator is usually called "cartridge."

Now it is the essential object of this invention to provide an improved spark plug of this general character and more particularly the above-defined cartridge which is characterized by a specific arrangement of the electrodes and insulator whereby the useful life and regularity of the spark plug are increased to a substantial extent.

According to a first characteristic feature of this invention, the electrodes consist of cylinders having different diameters which are separated from each other by an interval of constant or uniform width and depth, in which a detachable insulator fitted in a cavity of the grounded electrode is snugly fitted.

In order to afford a clearer understanding of the present invention and of the manner in which the same may be carried out in practice, reference will now be made to the single figure of the accompanying drawing illustrating diagrammatically in axial longitudinal section a typical embodiment of a low-tension spark plug constructed in accordance with the teachings of this invention.

In the drawing, the electrodes of the spark plug are designated by the reference numerals 1 and 2. The electrode 1 consists of a disk of refractory metal such as tungsten or thoriated tungsten, and the other electrode 2 consists of a hollow cylinder also of refractory metal. The electrode 2 is formed with an axial bore provided at one end with a cavity or counterbore forming a shoulder 3 and adapted to receive an insulating washer 4 constituting the spark supporting member seated on said shoulder. The diameter of this washer is very slightly smaller than that of the electrode 2. The interior of this electrode 2 is lined with insulating material 5 such as borosilicated glass up to the level occupied by the washer 4 bearing partly against this insulating lining and partly against the metal of the electrode 2. The insulator 5 may be fitted by compressing glass in the electrode carried by a jig. The electrodes 1, 2 are not necessarily of straight cylindrical shape with an annular cross-section, as the cylinder section may be designed to suit specific requirements of the combustion chamber. For the sake of economy the electrodes may be made not entirely of solid refractory metal but formed, for example, by welding a thin annulus of tungsten or thoriated tungsten on a steel body. The insulating washer 4 fits exactly in its recess or counterbore and may be slightly greater than this recess as measured in the axial direction; in this case the electrode 1 may have a greater diameter, or a diameter

2

equal to or less than that of the insulating washer. If desired, its height may be equal to or smaller than that of the recess; in both cases the diameter of this electrode 1 is smaller than that of the diameter of washer 4.

5 The spark-supporting insulator is not necessarily a flat hollow cylinder as the chief requirement is that its shape accommodate that of the electrode; besides, it may also completely fill the grounded electrode 2 and form a substitute for the insulator 5. The spark-supporting insulator 10 for 4 is preferably made of refractory material having a reliable stability up to 1000° C., that is, adapted to be heated to this temperature without melting, decomposing or undergoing any physical deterioration whatsoever; thus, porcelain, sintered alumina, clay-bound alumina, and 15 the like constitute efficient materials for this purpose.

If desired, insulating materials of high dielectric capacity may be used to advantage. The interelectrode gap *e* is of the order of 0.012" to 0.08" according to the type of insulating material utilized. The spark plug body 6 consists of a metal member insulated by a porcelain filling 8 and a "Bakelite" or like insulating cone 9 from the central steel tube 10 in which extends the current lead-in rod. The rod 7 is axially displaceable in tube 10". The insulator is constantly pressed between 20 the two electrodes by properly stacking at the upper end of the central rod 7 a plurality of spring-steel dished washers 11. These washers are disposed by pairs with their concavities facing each other and they exert a certain pressure against a sealing gasket 12 for example of 30 polytetrafluoroethylene; this pressure is obtained by means of an adequate nut 13 screwed on the rod 7.

Finally, the sparking surface may be enamelled with a suitable spark-supporting composition.

I claim:

- 35 1. In a low voltage spark plug having a tubular member, a spark-plug cartridge removably mounted in said body member comprising, a tubular first electrode disposed concentric internally of said tubular body member at one end thereof and extending axially externally thereof of at said end, said tubular electrode extending axially into said body member substantially a greater distance than the axial distance it extends outwardly of said body member, said tubular electrode having an axial bore with a counterbore in one end of the bore forming a shoulder 45 internally of said electrode, a washer-like insulator snugly, removably mounted coaxially with said electrode in said counterbore and seated on said shoulder, said insulator having a peripheral surface making contact with an annular inner surface of said first tubular electrode defining 50 said counterbore and having a substantially flat face coplanar with a substantially flat end of said electrode corresponding to said electrode end extending axially out of said body member, a disc electrode mounted coaxially with said tubular electrode and having a transverse dimension smaller than said insulator forming a circumferential gap of uniform dimensions between the disc electrode and the tubular electrode thereby forming a sparking zone of uniform dimensions, and an electrically conductive, axially displaceable, member disposed extending 55 axially in said tubular electrode and said body member and having a mushroom head for removably holding the disc electrode snug against said coplanar face surface of the insulator, means comprising a plurality of dished cooperatively disposed spring elements disposed externally 60 of the tubular body member for adjustably applying an axially directed tension to said electrically conductive member for causing the head thereof to apply pressure to said disc electrode in a direction pressing the disc electrode against said insulator, and an insulating composition circumferentially of said electrically conductive member filling said axial bore of the first electrode and extending axially in said tubular body member.

- 70

2. A low voltage spark plug according to claim 1, in which said insulator comprises a refractory material and is capable of remaining dimensionally stable at elevated temperatures at least to 1000° centigrade.

3. A low voltage spark plug according to claim 1, in which said insulator comprises a ceramic having a dielectric constant greater than 50.

4. A low voltage spark plug according to claim 1, in which said insulator is enamelled at least on said sparking zone with a spark-supporting enamel.

5. In a low voltage spark plug having a tubular member, a spark-plug cartridge mounted in said body member comprising, a tubular first electrode disposed concentric internally of said tubular body member at one end thereof and extending axially externally thereof at said end, said tubular electrode extending axially into said body member substantially a greater distance than the axial distance it extends outwardly of said body member, said tubular electrode having an axial bore with a counterbore in one end of the bore forming a shoulder internally of said electrode, a washer-like insulator mounted coaxially with said electrode in said counterbore and seated on said shoulder, said insulator having a peripheral surface making contact with an annular inner surface of said first tubular electrode defining said counterbore and having a substantially flat face substantially coplanar with a substantially flat end of said electrode corresponding to said electrode end extending axially out of said body member, a disc electrode mounted coaxially with said tubular electrode and having a transverse dimension smaller than said insulator forming a circumferential gap of uniform dimensions between the disc electrode and the tubular electrode thereby forming a sparking zone of uniform dimensions, and an electrically conductive, axially displaceable, member disposed extending axially in said tubular electrode and said body member and having a mushroom head for holding the disc electrode snug against said coplanar face surface of the insulator, means comprising a plurality of dished cooperatively disposed spring elements disposed externally of the tubular body member for adjustably applying an axially directed tension to said electrically conductive member for causing the head thereof to apply pressure to said disc electrode in a direction pressing the disc electrode against said insulator, and an insulating composition circumferentially of said electrically conductive member filling said axial bore of the first electrode and extending axially in said tubular body member.

6. A cartridge for a low voltage spark plug comprising, a tubular first electrode, said tubular electrode having an axial bore with a counterbore in one end of the bore forming a shoulder internally of said electrode, a washer-like insulator mounted coaxially with said electrode in said counterbore and seated on said shoulder, said in-

sulator having a peripheral surface making contact with an annular inner surface of said first tubular electrode defining said counterbore and having a substantially flat face substantially coplanar with a substantially flat end of said electrode corresponding to said electrode end having said counterbore, and a disc electrode mounted coaxially with said tubular electrode and having a transverse dimension smaller than said insulator forming a circumferential gap of uniform dimensions between the disc electrode and the tubular electrode thereby forming a sparking zone of uniform dimensions, and an insulating composition filling said axial bore of the first electrode.

7. A cartridge for a low voltage spark plug comprising, a tubular first electrode, said tubular electrode having an axial bore with a counterbore in one end of the bore forming a shoulder internally of said electrode, a washer-like insulator mounted coaxially with said electrode in said counterbore and seated on said shoulder, said insulator having a peripheral surface making contact with an annular inner surface of said first tubular electrode defining said counterbore and having a substantially flat face substantially coplanar with a substantially flat end of said electrode corresponding to said electrode end having said counterbore, a disc electrode mounted coaxially with said tubular electrode and having a transverse dimension smaller than said insulator forming a circumferential gap of uniform dimensions between the disc electrode and the tubular electrode thereby forming a sparking zone of uniform dimensions, and an electrically conductive, axially displaceable, member positioned in assembly in said spark-plug extending axially in said tubular electrode and having a mushroom head for holding the disc electrode snug against said coplanar face surface of the insulator, means comprising a plurality of dished spring elements cooperatively positioned in assembly on the spark plug for adjustably applying an axially directed tension to said electrically conductive member for causing the head thereof to apply pressure to said disc electrode in a direction pressing the disc electrode against said insulator, and an insulating composition circumferentially of said electrically conductive member filling said axial bore of the first electrode.
